UNITED STATES PATENT OFFICE.

JACOB T. JOHNSON, OF PHILADELPHIA, PENNSYLVANIA.

PULLEY.

No. 821,169.

Specification of Letters Patent.

Patented May 22, 1906.

Application filed July 17, 1905. Serial No. 270,084.

To all whom it may concern:

Be it known that I, JACOB T. JOHNSON, a citizen of the United States, residing at Philadelphia, in the county of Philadelphia and 5 State of Pennsylvania, have invented a new and useful Pulley, of which the following is a specification.

This invention relates to automatic-locking pulleys, and has for its principal object to 10 provide a pulley that is particularly adapted for use in connection with spring-closed awnings, the pulley being so constructed and mounted on the upper edge of the window-sill as to insure the proper guiding of the awning- 15 operating cord or rope.

A further object of the invention is to provide an automatic-locking pulley with a supporting-base and guard, so constructed as to permit the securing of the pulley in proper 20 position.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size, and minor details of the 25 structure may be made without departing from the spirit or sacrificing any of the advantages of the invention.

In the accompanying drawings, Figure 1 is a general perspective view showing an automatic-locking pulley constructed in accordance with the invention and illustrating its employment for the purpose of guiding and locking the operating cord or rope by a spring-closed window-awning. Fig. 2 is a plan 35 view of the pulley. Fig. 3 is a front elevation of the same. Fig. 4 is a vertical section of the pulley and its supporting-base.

Similar characters of reference are employed to indicate corresponding parts 40 throughout the several figures of the drawings.

The device forming the subject of the present invention is adapted particularly for use in connection with awnings of the type 45 shown in Fig. 1, wherein the awning x is secured to a frame y , substantially U-shaped in form, the inner ends of the arms of the frame being coiled to form torsion-springs and being connected to the window-frame in 50 such manner that if left free the frame will move to the vertical position and close the

awning. The outer portion of the frame is connected to an operating cord or rope z , the lower portion of which extends partly around and is guided by the pulley 10, while the inner end of the cord leads within the room and in convenient position to be manipulated in lowering or raising the awning and for locking the same in any position to which it may be adjusted. The strain on the cord or rope 55 due to the peculiar construction of the awning is such that considerable difficulty is found in the employment of cord guiding and locking devices of the ordinary type, and in carrying out the present invention the self-locking pulley 10 and its supporting-base are so arranged as to permit the proper guiding of the cord and to allow locking of the same with the awning in any position of adjustment. 70

The pulley is provided with a base-plate 11, near the outer ends of which are arranged openings 12 for the passage of screws or other securing devices, which are driven into the upper surface of the window-sill. At the front 75 of the base-plate is a depending flange 12', arranged, preferably, at a right angle to the base and provided with a central opening 13 for the passage of a screw, so that the pulley may be firmly secured in place to the outer 80 front edge of the sill and all downward and upward strains effectually resisted. Extending upward from the base-plate is a pair of spaced standards 14, having openings for the reception of the end pintles 15 of a pulley 10, 85 and said pulley is provided with a centrally-disposed annular groove 16, around which the cord is guided and on which the cord is free to run so long as it is maintained at a right angle to the axis of the pulley. The 90 periphery of the pulley is also provided with one or more locking-grooves 17, leading from the central groove toward the edge of the pulley and forming cam-surfaces, which, in connection with the adjacent upper face of the base-plate, form clamps for locking the cord when the inner end of the latter is drawn to one side or the other of the groove 95 16. In order to permit free passage of the cord while the latter is maintained in the annular groove 16, the central portion of the base-plate is provided with a transversely-extending groove 19, which may terminate short of the outer edge of the plate, this groove, in connection with the annular groove 100 16, forming a space of much greater width than the diameter of the cord; but if the cord

is drawn to one side or the other it will travel in one of the cam-grooves 17 and be moved directly against the surface of the base-plate and firmly locked in position.

- 5 To further assist in guiding the cord, the standards 14 are provided with inwardly-projecting guiding-wings 19', fitting over the ends of the pulley and being spaced from each other for a distance approximately 10 equal to the width of the annular groove 16. These guards or guides extend from the front edge of the base-plate upward over the front and slightly over the top of the pulley, the 15 length of the guides insuring the proper positioning of the cord within the groove 16 without regard to the various angular positions of the cord during the movement of the awning from open to closed position, or vice versa.
- 20 During the movement of the awning from closed to open position the outer portion of the cord extends first in a practically vertical plane, and as the awning is pulled down the cord moves outward to an angle of approximately 25 sixty degrees; but it will be noted that the wings or guards 19' are arranged to cover rather more than this arcuate distance, so that the cord is at all times properly guided to the annular groove 16 and there 30 will be no danger of entangling or knotting of the cord at the outer side of the pulley. It is only when the inner end of the cord is drawn sidewise with respect to the pulley and allowed to move outward that said cord 35 is gripped between one of the cam-grooves 17 of the pulley and the adjacent surface of the base-plate.

The construction of the base is such that the pulley may be securely held to the outer 40 upper edge of the window-sill and the secur-

ing devices arranged in the best position to effectively resist the strain on the cord.

Having thus described the invention, what is claimed is—

1. In combination, a base-plate having a 45 downwardly-extending flange at its front edge, the plate and flange being provided with openings for the passage of securing devices, a pair of spaced standards carried by the base-plate, a self-locking pulley mounted 50 between said standards, and cord guides or guards extending inward from the standards over the front face of the pulley, said guards being spaced from each other at the central portion of the pulley to permit the free passage of the cord.

2. In combination, a base-flange having a pendent flange at its forward edge, the plate and flange having openings for the passage of securing devices, a pair of spaced standards rising from the base-plate, a self-locking pulley mounted in the standards and having a centrally-disposed peripheral groove, there being a similar groove formed in the upper face of the base-plate at a point opposite said 60 annular groove, and a pair of cord-guides extending inward from the standards and spaced from each other a distance approximately 65 equal to the width of said annular groove, said guides extending from the base-plate upward over the front and a portion of the top of the pulley.

In testimony that I claim the foregoing as my own I have hereto affixed my signature in the presence of two witnesses.

JACOB T. JOHNSON.
